HOSE CONNECTER FOR VACUUM CLEANERS

George W. Allen, Hyde Park, Mass., assignor to
 B. F. Sturtevant Company, Hyde Park, Mass.,
 a Corporation of Massachusetts

Application May 19, 1930. Serial No. 453,842

15 Claims. (Cl. 15—9)

The present invention relates to vacuum cleaners and more particularly to adapters or hose connectors for domestic cleaners of the traveling type whereby a flexible suction hose provided with a hand nozzle or tool may be detachably connected to the cleaner for the cleaning of upholstery, curtains and the like.

The object of the present invention is to provide an adapter or connector which may be connected directly to the suction nozzle itself of the cleaner, and which may be easily and quickly attached or removed.

A further object is to provide a hose connector which is especially adapted for use upon a well-known type of cleaner having a suction nozzle with inlet openings or ports for supplying air to the fabric being cleaned adjacent the inlet or suction mouth of the nozzle, as shown and described in the pending application for Letters

20 Patent filed by George W. Allen and Lena B. Allen on August 27, 1929, Serial No. 388,729.

With these objects in view the present invention consists in the devices and combinations of devices hereinafter described and more particularly defined in the claims.

In the accompanying drawings which illustrate what is now considered the preferred form of the present invention as embodied in a hose connector adapted for use on the suction nozzle shown and described in said application, Fig. 1 is a side elevation of a cleaner with the adapter attached thereto; Fig. 2 is a top plan view on an enlarged scale of the front portion thereof; Fig. 3 is a transverse vertical sectional view on line 3—3 of Fig. 2; Figs. 4 and 5 are longitudinal, vertical sectional views on lines 4—4 and 5—5 respectively of Fig. 2; and Fig. 6 is a perspective view of the hose connector detached.

The cleaner illustrated in Fig. 1 comprises the usual fan casing 6, with the forward and downward extension 7, flaring laterally into the nozzle 8. An electric motor 9 is mounted on the top of the casing, and the rear end of the machine is supported by the wheels 10. The dust bag 11 and propelling handle 12 are shown only in part.

The nozzle, as shown in said Allen application and as illustrated in Figs. 4 and 5 of the present drawings, comprises the inlet slot or mouth 14 extending across substantially the entire width of the nozzle and communicating with the interior of the fan casing 6 through the usual dust or passage within the part 7. Adjacent the nozzle mouth at the front and rear are the air ports or openings 16 through which air is de-

livered from the inlet ports 17 onto the surface of the fabric being cleaned to loosen any threads or dirt upon or in the fabric and to carry the same into the suction mouth. An endless rubber bumper band 18 is held in the recess of 60 groove 19 in the front, rear, and end walls of the nozzle.

In normal operation the front end of the cleaner is supported by the flat bottom faces 18 which form part of the nozzle structure, all as 65 shown and described in said Allen application.

The adapter or hose connector which forms the subject of the present invention is adapted not only to cover and close the suction or inlet mouth of the nozzle, but also to cut off the air 70 ports or openings at the front and rear thereof. In addition it is provided with means for quickly and securely clamping on the nozzle where it supports the front end of the cleaner and maintains the apparatus in upright position. 75

As shown in Fig. 6, the adapter or connector comprises a trough-shaped body portion having substantially vertical side walls 22 and a bottom consisting of the flat end portions 24 and a deeper middle or intermediate portion 26. This intermediate portion has its bottom inclined inwardly from each end, as at 27, and curved downwardly and forwardly from the rear, as at 28. At the bottom of the front wall is the tubular extension or fitting 29 to receive the suction 80 hose 30, as shown in Fig. 1.

At each end of the adapter is a small air opening 31 in the vertical wall for the purpose of admitting a current of air which will prevent the lodgment and deposit of dust or dirt at the 85 ends of the adapter.

The adapter is provided near each end with supports or legs 32 which consists of U-shaped members having a stiffening rib or lip 34 at each edge, the upper ends of the vertical members being connected as by spot welding to the front and rear walls. The height of these legs is such that the adapter and front end of the cleaner are supported solely by these legs, the lower middle portion 26 being above and out of contact with the floor or other surface: Owing to the wide spacing apart of these legs on the adapter, the cleaner is maintained securely in erect position without danger of being tipped over even when it 95 is drawn about by the hose. These supporting legs are of such a width and their front and rear bottom corners are so rounded that little resistance is offered to the movement of the cleaner and the latter may be drawn about by 100 105 110 115

the hose with a minimum of effort, even over deep pile fabric.

The converter is connected or attached to the nozzle by means of the spring clips 36 pivoted at their rear ends to the top of the rear vertical members of the supporting legs. These members are formed with two extensions or lugs at their tops spaced from one another and rolled over to provide the cylindrical supports 40 for the pivot pin 42.

The free ends of the clips are formed with a rounded catch or shoulder 44 to engage beneath the bead or out-turned lip 45 on the top edge of the vertical walls of the adapter. An extension or thumb piece 46 facilitates the engagement and disengagement of the catch or shoulder and the lip when it is desired to attach or remove the adapter. The horizontal or body portion of the clip is struck downwardly to form the rounded rib 48 to engage the top of the nozzle, as shown in Fig. 5, when the clip is in operative position, thus holding the adapter tightly on the nozzle by the spring of the clips.

In normal operation of the cleaner, that is, when it is being propelled over a rug to clean the same, the adapter or hose connection is not attached and the nozzle rests directly upon the rug. When however, it is desired to use the flexible hose with the hand tool, the front end 30 of the cleaner is slightly raised, the adapter with the connected hose already attached is positioned beneath the nozzle, which is then lowered into place in the trough-shaped body of the adapter, the spring clips are turned over the top of the nozzle and forced into operative position beneath the lip on the walls, and the cleaner is ready for use with the hose and hand tool.

The spring action of the attaching clips 36 holds the connector and nozzle in close yielding engagement, with the rubber bumper band 118 compressed between the nozzle and the walls of the converter to prevent any leakage of air downwardly therebetween.

By reason of the flat bottom end portions 24, 45 which when the converter is in position on the nozzle are in close proximity to the bottom of the nozzle, and of the lower middle portion 26, the cross sectional area of the air duct or passage through the converter is restricted and the 50 formation of pockets or dead spaces is avoided, thus preventing reduction of air velocity and the resulting deposit of dust and dirt.

The converter of hose connector herein shown and described may conveniently be stamped from sheet material with corresponding light weight and reduced cost of manufacture. It is self-contained, that is, it has no loose or separate parts to be mislaid or lost, and requires no movable or disconnectible parts on the cleaner.

While the adapter herein shown and described is especially designed for use with the nozzle of said Allen application, it is obvious that it may be used with other types of nozzles, and may be embodied in other forms and arrangements within the scope of the appended claims.

Having thus described the invention, what is claimed is:

1. A hose connector for a vacuum cleaner nozzle comprising a body portion having a bottom and side walls to enclose the cleaner nozzle, elastic material between the nozzle and said walls, and means for securing the connector to the nozzle.

2. A hose connector for a vacuum cleaner nozzle comprising a body portion having a bot-

tom and side walls to enclose the cleaner nozzle, the top of the walls being formed with an outwardly flaring, packing-engaging lip, an elastic band encircling the nozzle and engaged by the lip and means for securing the connector to the nozzle.

3. A hose connector for the nozzle of a vacuum cleaner comprising a body having a bottom and side walls to loosely enclose the cleaner nozzle, a tubular hose extension in a side wall, and pivoted yielding devices adapted to engage the top of the nozzle for securing together the connector and the nozzle.

4. A hose connector for vacuum cleaners comprising a body portion adapted to be connected to the nozzle of the cleaner, and provided with a hose extension, and a U-shaped supporting leg secured to the front and rear faces of the body portion adjacent each end of the connector for supporting the body portion and extension above the plane of the bottom of said legs, the front and rear bottom corners of the legs being rounded to facilitate movement of the connector over the surface upon which it rests.

5. A hose connector for vacuum cleaners comprising a body having a bottom and side walls, a tubular hose extension from one of said walls, U-shaped legs adjacent each end of the body for supporting the connector, the upper ends of said legs being secured to the side walls, and one of said ends being formed with two extensions rolled over into cylindrical hinge members, and a spring clamp pivotally connected with said hinge members for securing the connector to the cleaner nozzle.

6. A vacuum cleaner having, in combination, a nozzle, a hose connector therefor comprising a body having a bottom and side walls, a tubular hose extension from one side thereof, elastic material between the nozzle and the side walls, and means for securing together the nozzle and the connector with the elastic material under compression.

7. A vacuum cleaner having, in combination, a nozzle, a hose connector comprising a body having a bottom and side walls, a tubular hose connection from one side of the body, elastic material between the side of the nozzle and the side walls of the connector, and yielding means for securing together the nozzle and the connector with the elastic material under compression.

8. A vacuum cleaner having, in combination, a suction nozzle having an auxiliary air inlet in the side thereof, a hose connector having a bottom, side walls, and a tubular hose extension, means for securing the connector to the nozzle with the side walls extending above the air inlet, and elastic material between the nozzle and the side walls and above said inlet to prevent air leakage.

9. A vacuum cleaner having, in combination, a nozzle having an external groove on the side walls thereof, a band of elastic material in the groove, a hose connector comprising a body having a bottom, side walls, and a tubular hose extension therefrom, and means for securing the connector to the nozzle with the elastic band in engagement with the side walls of the connector to prevent air leakage.

10. A vacuum cleaner having, in combination, a nozzle provided with an external groove on the front, rear, and end walls thereof, a band of elastic material in the groove, a hose connector having a bottom, side walls, and a hose exten-

- sion, the side walls having a top, outwardly flaring lip, and a spring clip pivoted at one side of the connector and adapted to detachably engage the opposite side for securing the connector to the nozzle with the elastic band in close contact with groove and lip to prevent air leakage therebetween. 11. A hose connector for the nozzle of a vacuum cleaner comprising a body having a bottom and side walls, and a tubular extension from one wall intermediate its ends, the walls at each end of the connector being provided with an air opening to admit air. 12. A hose connector for the nozzle of a vacuum cleaner comprising a body having a bottom and side walls, the portions of the bottom adjacent the ends being above the intermediate portion of the bottom, a tubular extension from the side wall opposite the intermediate portion of the bottom, and means for securing together the nozzle and the connector with the bottom of the nozzle in close proximity to the end portions of the bottom of the connector, the walls at each end of the connector being provided with an air opening adjacent the bottom to admit air. 13. A hose connector for the nozzle of a vacuum cleaner comprising a body having a bottom and side walls to loosely enclose the cleaner
- nozzle, a tubular hose extension in a side wall, and yielding devices carried by the connector adapted to engage the nozzle for securing together the connector and the nozzle. 14. A hose connector for vacuum cleaners comprising a body portion adapted to be connected to the nozzle of the cleaner, and provided with a hose extension, and a U-shaped supporting leg secured to the body portion adjacent each end of the connector for supporting the body portion and extension above the plane of the bottom of said legs, the front and rear corners of the legs being rounded to facilitate movement of the connector over the surface upon which it rests. 15. A vacuum cleaner having, in combination, a nozzle provided with an external groove on the front, rear and end walls thereof, a band of elastic material in the groove, a hose connector having a bottom, side walls, and a hose extension, the side walls having a top, outwardly flaring lip, and a spring clip carried by the connector and adapted to detachably engage the nozzle for securing the connector to the nozzle with the elastic band in close contact with the groove and the lip to prevent leakage therebetween.
